Primary Examiner — Austin Murphy(74) *Attorney, Agent, or Firm* — Hemisphere Law, PLLC; Zhigang Ma(57) **CLAIM**

The ornamental design for an USB device, as shown and described.

DESCRIPTION

FIG. 1 is a front elevational view of an USB device showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, top, right side perspective view thereof;

FIG. 8 is a rear, top, left side perspective view thereof;

FIG. 9 is a front, bottom, right side perspective view thereof;

FIG. 10 is an enlarged view of a part 10 of the USB device in FIG. 9; and,

FIG. 11 is rear, bottom, left side perspective view thereof. The broken lines are employed to illustrate environmental structures and form no part of the claim.

1 Claim, 8 Drawing Sheets(56)
